Primary Examiner — Susan Moon Lee*(74) Attorney, Agent, or Firm* — K. Gibner Lehmann**CLAIM**

The ornamental design for a combined salt lick and horse halter holder, substantially as shown and described.

DESCRIPTION

FIG. 1 is a perspective view of the combined salt lick and horse halter holder showing my new design, installed on a rail of a stall.

FIG. 2 is a perspective view of the combined salt lick and horse halter holder.

FIG. 3 is a front elevation of the combined salt lick and horse halter holder.

FIG. 4 is a top plan view of the combined salt lick and horse halter holder.

FIG. 5 is a left side elevation of the combined salt lick and horse halter holder, the right side elevation being a mirror image thereof.

FIG. 6 is a rear elevation of the combined salt lick and horse halter holder; and,

FIG. 7 is a bottom plan view of the combined salt lick and horse halter holder.

Broken lines and portions contained within broken line are not claimed.

1 Claim, 7 Drawing Sheets(56)
